UNITED STATES PATENT OFFICE.

DUNCAN MACPHERSON, OF MONTREAL, CANADA.

SHED FOR ENGINES, &c.

No. 798,814.

Specification of Letters Patent.

Patented Sept. 5, 1905.

Application filed August 12, 1904. Serial No. 220,577.

To all whom it may concern:

Be it known that I, DUNCAN MACPHERSON, of the city of Montreal, district of Montreal, and Province of Quebec, Canada, have invented certain new and useful Improvements in Sheds for Engines or Railway Motor-Vehicles; and I do hereby declare that the following is a full, clear, and exact description of the same.

10 My invention has for its object to provide in substitution for the circular shed heretofore used a rectangular shed for the storage of engines or railway motor-vehicles generally, such as electric cars or the like.

15 The invention may be said to consist of a rectangular and preferably oblong shed having first a series of longitudinal parallel tracks extending from end to end of its floor-space and terminating at one end outside of 20 the shed in preferably a single track common to all the longitudinal tracks, and in combination with the longitudinal series a second series of diagonal parallel tracks, one of which tracks extends diagonally across the floor-space from one corner thereof to another and intersects the tracks of the first-mentioned 25 series and the others of which, of less length, also extend diagonally from one point to another on the first series. These diagonal 30 tracks enable an engine or the like to be moved from one of the longitudinal tracks to another and thence out of the shed or completely across such longitudinal tracks—say from one innermost rear corner of the floor-space to a 35 diagonally opposite outermost corner, or vice versa—and they also allow an engine or the like to be moved while within the shed from one pit to any other pit, of which there are a number under each longitudinal track. If desired, 40 a single diagonal track can be used instead of a series, but less advantageously.

For full comprehension, however, of my invention reference must be had to the accompanying drawings, forming a part of this 45 specification, in which similar reference characters indicate the same parts, and wherein—

Figure 1 is a diagrammatical plan view of an engine-shed constructed according to my invention. Fig. 2 is a transverse vertical 50 sectional view thereof.

My oblong rectangular shed may be built of any desired material and comprises end walls b , side walls c , and roof d , one of the end walls being provided with a series of doors e . A series of parallel tracks g , g' , g^2 , g^3 , g^4 , g^5 , and g^6 extend longitudinally from end to

end of the shed and out through the doors and preferably converge to a common point, where they terminate in a single track h , while a second series of parallel tracks i , i' , i^2 , i^3 , i^4 extend diagonally across the longitudinal series, and the points of intersection of these two series are provided with slip-switches k , which enable any engine or the like to be moved out without disturbing the others. 65

A series of pits m of the kind usually required for repairs or cleaning are sunk in the floor of the shed between the rails of each of the longitudinal tracks, and an additional function of the diagonal rails is to enable an 70 engine or the like to be moved from one of the pits to any other pit of the series without leaving the shed.

The advantages attendant upon my improved construction of shed is that, first, in case 75 of fire a full shed of, say, forty-two engines can be run out of danger in an exceedingly short space of time even if only one engine on each track is under steam; secondly, no turn-table is required to stall the engines, and a Y n can 80 be utilized and the turn-table dispensed with, which reduces the initial expense and cost of maintenance and operation, and, thirdly, a less costly building will suffice, as fewer doors are 85 required than in the usual circular shed, thus dispensing with a considerable number of windows and avoiding the breakage thereof.

If desired, the main diagonal track i^2 alone may be used and the other tracks i , i' , i^3 , and i^4 of the series dispensed with, but less advantageously.

What I claim is as follows:

1. A rectangular shed having its floor-space laid with a series of parallel tracks extending longitudinally of the shed from end to end thereof, a second series of diagonal parallel tracks one of which diagonal tracks extends diagonally across the longitudinal tracks from one corner of the floor-space to another and means whereby the tracks of the diagonal series are caused to communicate with the tracks of the longitudinal series, substantially as described and for the purpose set forth. 95

2. A rectangular shed having its floor-space laid with a series of parallel tracks extending longitudinally of the shed, from end to end thereof, a second series of diagonal parallel tracks, one of which diagonal tracks extends diagonally across the longitudinal tracks from one corner of the floor-space to another, and a series of slip-switches located at the points of intersection of the tracks of one series with 100 105 110

the tracks of the other series, substantially as described and for the purpose set forth.

3. A rectangular shed having its floor-space laid with a series of parallel tracks extending longitudinally from end to end thereof, a second series of diagonal parallel tracks, one of which diagonal tracks extends diagonally across the longitudinal tracks from one corner of the floor-space to another, the floor-space of the shed having a series of pits between the rails of each of the longitudinal tracks, and means whereby the tracks of one series are caused to communicate with the tracks of the other series, substantially as described and for the purpose set forth.

4. A rectangular shed having its floor-space laid with a series of parallel tracks extending longitudinally from end to end thereof, a second series of diagonal parallel tracks extending diagonally across the longitudinal tracks, the floor-space of the shed having a series of pits between the rails of each of the longitudinal tracks, and means whereby the tracks of one series are caused to communicate with the tracks of the other series so that an engine, or the like, can be moved from one pit to any other pit of the series, substantially as described and for the purpose set forth.

5. A rectangular shed having its floor-space

laid with a series of parallel tracks extending longitudinally from end to end thereof, a series of parallel tracks extending diagonally across the longitudinal tracks, the floor-space of the shed having a series of pits between the rails of each of the longitudinal tracks, and a series of slip-switches located at the points of intersection of the tracks of one series with the tracks of the other series whereby an engine, or the like, can be moved from one pit to any other pit of the series, substantially as described and for the purpose set forth.

6. A rectangular shed having its floor-space laid with a series of parallel tracks extending longitudinally from end to end thereof, a diagonal track extending from one corner of the floor-space to another diagonally across said longitudinal tracks, and means whereby the longitudinal tracks are caused to communicate with said diagonal track, substantially as described and for the purpose set forth.

In testimony whereof I have affixed my signature in presence of two witnesses.

DUNCAN MACPHERSON.
